UNITED STATES PATENT OFFICE.

ROY T. MORGAN, OF ST. LOUIS, MISSOURI.

SPRING-WHEEL.

1,276,679.

Specification of Letters Patent. Patented Aug. 20, 1918.

Application filed June 12, 1916. Serial No. 103,070.

To all whom it may concern:

Be it known that I, ROY T. MORGAN, a citizen of the United States of America, and a resident of the city of St. Louis and State 5 of Missouri, have invented certain new and useful Improvements in Spring-Wheels, of which the following is a specification.

The primary object of this invention is to provide a spring wheel with an improved 10 arrangement of resilient members.

Another object of this invention is to provide an improved manner of mounting the resilient members to the parts which they are to be secured to relative to the construction 15 of a spring wheel.

A further object of this invention is to provide an improved spring wheel which can be quickly assembled, and in which the resilient members are secured in place without 20 the aid of bolts or clasps.

Other and further objects will appear in the specification and be specifically pointed out in the appended claims, reference being had to the accompanying drawings exemplifying the invention, and in which,

Figure 1 is a side elevation of this improved spring wheel, a portion thereof being broken away.

Fig. 2 is a transverse section taken on the 30 line II—II of Fig. 1.

Fig. 3 is a section taken on the line III—III of Fig. 1.

Fig. 4 is an inverted section taken on the 35 line IV—IV of Fig. 1.

Fig. 5 is an elevation of one of the springs which is used in the construction of this improved wheel.

Referring to the drawings, 1 designates the inner hub, 2 the outer hub or resilient 40 retaining ring, and 3 the felly to which any suitable type of tire 4 can be mounted. Formed in the hub 1 are a series of horizontally arranged holes or pockets 5, said holes being arranged concentrically around 45 the bore 6 of said hub, each of said holes being for the reception of an engaging portion 7 of a resilient member 8, there being a plurality of said members 8 arranged in pairs radially around said hub 1. Each of 50 the resilient members 8 comprises a length of round spring wire of the proper weight which is bent on itself forming a coil 9, said wire continuing in an approximate straight line after the coil has been made, and terminating into a loop 10, said loop being oppositely disposed to the engaging portion 7.

As afore stated, these resilient members 8 are arranged in pairs radially around the hub 1, each engaging portion 7, of each of the members forming a pair, being introduced into their respective holes 5 on opposite sides of the hub, in which each pair will form a triangular mounting, (see Fig. 2), in which the loops 10 of a pair of members 8 will be mounted in a slot 11, there being a series of such slots arranged at equal distances apart in the outer hub 2. These loops 10 when mounted in pairs in their respective slots 11 are adapted to be engaged over an annulus 12, which is centrally arranged on the outer periphery on said outer hub 2.

In order to prevent radial displacement of each of the members 8, a notch 13 is formed adjacent each of the holes 6 in the outer periphery of the hub 1. Formed in the periphery of the outer hub 2 adjacent each side edge thereof is a series of circularly arranged slots 14, each of said slots being for the reception of an inner end loop 15 of a resilient member 16, each of said resilient members being arranged in pairs, and arranged radially around the outer hub 2, each of said members 16 having a transversely arranged portion 17 formed on their outer ends, each of said transverse portions 17 being mounted in an opening 18, there being a plurality of said openings formed in the felly 3.

Mounted adjacent each set of circularly arranged slots 14, and against the inner periphery of the outer hub 2 is an annulus 21, said annuli adapted to be engaged by the looped ends 15 of the members 16. These resilient members 16 are similar in construction to the resilient members 8, (see Fig. 5), which has been designated as one of the members 8, the portions 7 and 10 thereof being very similar to the portions 15 and 17, respectively, of the resilient member 16, and the coil 9 representing the coil 19 of said member 16. In order to facilitate the mounting the parts of this improved wheel together, the outer hub 2 is preferably split as designated at 20.

When an improved wheel of this character has been mounted together as described, it is readily seen how the outer ends of the resilient members 8 will hold the annulus 12 in place, whereas said annulus 12 in turn with the circularly arranged slots 11 will support the outer ends of said members 8,

2
and the annuli 21, while supporting the inner ends of the resilient members 16, are in turn supported by said inner ends, in view of the fact that the resilient members 8 and 16, which will be above the inner hub 1, will be under tension in which the weight of the car or vehicle carried by said inner hub will be suspended from the outer hub 2 and felly 3, thereby providing great resiliency combined with a maximum efficiency in resisting abnormal strains. Since the upper resilient members 8 and 16 are under tension, it is to be seen that when a vehicle equipped with this improved spring wheel is moved downwardly that the lower resilient members 8, which will be directly beneath the load, will be forced downwardly. In this connection, said members will not be under compression on account of the fact that the engaging ends of said members 8, relative to their engagement with the outer hub 2, will slide downwardly through their respective slots 11, thereby compensating for the resiliency of the outer hub 2, and as said outer hub is moved downwardly, the inner ends of the members 16, which are also beneath the load will be forced upwardly through their respective slots 14.

What I claim is:

- 30 1. In a spring wheel, an inner and an outer hub, said outer hub comprising a resilient ring, a plurality of resilient members radially arranged between said hubs, an annulus carried by said outer hub, said resilient members having their outer ends slidably secured to said annulus and said outer hub, said annulus providing means for securing said resilient members to said outer hub.
- 40 2. In a spring wheel, an inner hub and an outer hub, said outer hub comprising a resilient ring and having a series of apertures formed in the periphery thereof, a plurality of resilient members located between said hubs, an annulus mounted on the outer periphery of said outer hub, said resilient members having their outer ends slidably mounted in said apertures of said outer hub and engaging said annulus, said annulus providing means for securing said resilient members to said outer hub.
- 50 3. A spring wheel comprising an inner hub, an outer hub and a felly, said outer hub comprising a resilient ring and having a series of apertures formed in the periphery thereof, a plurality of resilient members located between said hubs, one end of each of

said resilient members having a hook shaped portion formed thereon, each of said hook shaped portions being extended through some of said apertures of said outer hub, an annulus mounted on the outer periphery of said outer hub in engagement with said hook shaped portions of said resilient members, and a plurality of resilient members having hook shaped portions located between said outer hub and said felly, said hook shaped portions of said last mentioned resilient members extending through said other apertures of said outer hub, and a pair of annuli mounted against the inner periphery of said outer hub for engagement with said hooked portions of said last mentioned resilient members.

4. A spring wheel comprising an inner hub, an outer hub and a felly, said outer hub comprising a resilient ring, a plurality of resilient members located between said inner hub and said outer hub, an annulus mounted on the outer periphery of said outer hub having a sliding engagement with the outer ends of said resilient members, a pair of annuli located adjacent the inner periphery of said outer hub, a plurality of resilient members located between said outer felly, said pair of annuli having a sliding engagement with the inner ends of said second mentioned resilient members.

5. A spring wheel comprising an inner hub, an outer hub and a felly, said outer hub comprising a resilient ring, a plurality of resilient members located between said inner hub and said outer hub having hook shaped portions formed on their outer ends, an annulus mounted on the outer periphery of said outer hub for engaging said hooked portions of said members, a pair of annuli located adjacent the inner periphery of said outer hub, a plurality of resilient members located between said outer hub and said felly having hook shaped portions formed on their inner ends for engagement with said annuli, a transversely arranged portion formed on the inner end of each of said first mentioned resilient members, said transversely arranged portions adapted to engage the side walls of said inner hub, a transversely arranged portion formed on the outer end of each of said second mentioned resilient members, said transverse portions of said second mentioned resilient members adapted to engage the side walls of said felly.

ROY T. MORGAN.
